UNITED STATES PATENT OFFICE.

SINCLAIR J. JOHNSON, OF NUTLEY, NEW JERSEY.

DUST-GUARD.

SPECIFICATION forming part of Letters Patent No. 685,382, dated October 29, 1901.

Application filed December 1, 1900. Serial No. 38,288. (No model.)

To all whom it may concern:

Be it known that I, SINCLAIR J. JOHNSON, a citizen of the United States, residing in Nutley, in the county of Essex and State of New Jersey, have invented certain new and useful Improvements in Dust-Guards, of which the following is a specification.

This invention relates to improvements in dust-guards for journal-boxes, it being particularly adapted for use in connection with railway-cars and the like, and has for its object the provision of such a device which shall be efficient in keeping the dust from the bearing and in which portions of the guard may be readily renewed.

In the drawings accompanying this specification, Figure 1 is a side elevation of a journal-box with a dust-guard made according to the present invention, the portion of the box surrounding the guard and the guard itself being in section. Fig. 2 is a vertical section of the guard on the line *a a* of Fig. 3. Fig. 3 is an enlarged side elevation of the guard, parts being broken away. Fig. 4 is an enlarged end elevation of a portion of the journal-box. Fig. 5 is the top plan view thereof. Fig. 6 is a partial elevation of another form of the invention, one of the frame-plates being removed. Fig. 7 is a vertical section on a line *b b* of Fig. 6. Fig. 8 is a detail showing the means for fastening a facing-strip to the frame.

Similar characters designate like parts in the different figures of the drawings.

One form of my invention is shown in connection with a journal-box, (designated in a general way by *B*,) in which is mounted a journal *J*. This box may be of any desired form, but is preferably one which is provided at or near its inner end with a chamber *B'* to receive the dust-guard, (designated as a whole by *D*.) The opening at the top of the chamber *B''* may be closed by a removable cover *B'''*.

The dust-guard comprises a frame, here shown as made up of metal side plates 11, 11, and intermediate filling pieces or blocks 12, preferably of wood, closing three sides of the frame and having an opening 12' at the remaining side. Instead of being made in a plurality of pieces the piece 12 may be formed or molded of any desired material in one piece. Rivets 13, passed through the

plates and blocks, fasten the parts together. Through each of the plates 11 is an opening 14 to receive the journal, it being preferably 55 of slightly greater diameter than said journal. The portion of the blocks 12 which surrounds the opening is shaped to conform to it, the diameter of this opening in the blocks being larger than that in the plates. This forms an 60 annular channel in which is placed a packing or guard strip 15, of any flexible material which will conform itself to the journal, it being shown herein as a fibrous substance—felt, for example. This strip substantially 65 fills the width of the channel and projects more or less within the edge of the opening 14. Within the frame, in proximity to the opening 12', occupying substantially the full width and extending a portion of the distance 70 between the blocks 12', which are shown as extending up beyond the journal-opening at this point, is a rigid wear-resisting supporting member 16. In Figs. 2 and 3 this block is shown as riveted in place between the 75 side plates, similarly to blocks 12; but it may be otherwise supported, as will be later explained. The member 16 may consist of a block 16', provided with a shoe 17, of steel or other desirable wear-resisting material, upon 80 its inner surface, curved to fit the journal. The flexible guard-strip at the ends of the channel passes up between the member 16 and the blocks 12, producing with the former a practically continuous surface embracing 85 the journal.

To secure the guard-strip in place, it is preferably connected to the member 16 and for this purpose may be provided with a flexible backing or band 18, to which it is secured. 90 This extends beyond the guard-strip at each end and may be attached to hooks or catches 19 upon the outer side or top of the member 16, which catches preferably have a spring action and exert their force upward. 95

To the edge of the frame on the sides and across one face, near the top, is preferably attached a facing-strip of fabric 20, which is doubled to produce a piped or tubular edge 21, which projects a substantially uniform 100 distance from one face of the frame. This fabric may be tacked in place with an outer securing-strip 22, of thin sheet metal.

In the use of the dust-guard it is introduced

in place when the journal and its box are assembled, it being placed in its chamber and the journal passed through the openings 14. The member 16 then rests upon the top of the journal. Its shoe, if one be employed, contacting therewith supports the guard and closes a portion of the opening, while the strip 15 is drawn tightly about the remaining portion against the ends of the member by the circumferential tension produced in it by the spring-catches and completes the closure, preventing dust from entering about the axle. As the guard becomes worn this tension in the spring-supports takes up the strip and maintains the contact. If material were used which wore slowly, the strip might be fastened to rigid instead of spring catches. When the flexible guard-strip is worn through, or nearly so, it may be withdrawn by the band attached to it and a new one drawn into the channel without removing the guard-frame from its chamber by attaching its band to that of the one removed or by a wire or the like passed through the channel.

25 The frame is of such thickness relative to the containing-chamber that when it is in place the tubular edge 21 is pressed against one side of the chamber, while the opposite face of the guard rests against the other. 30 The compression of this edge renders this facing-strip capable of adjusting itself to the inequalities of the surface and completes the closure of the journal-box.

In Figs. 6 and 7 a construction is shown whereby the member 16 may be removed from the frame for renewal or to more readily introduce the guard-strip. This may be effected in various ways, two of which are shown. In one, movable pieces, shown as flat 40 springs 23, are mounted in grooves on each side of the member and carry projections 24, engaging openings in the side plates 11. In the other, similar springs 25 are attached to the end of the member and are provided with 45 projections 26, adapted to enter openings in angle-bars 27, secured to the side plates. In either case the pressing of the springs inward releases the member and permits its withdrawal.

50 Either of the above devices may be used alone to secure the member, or, if desired, both may be employed.

Although the strip 15 is shown as but partially encircling the journal, it is evident that 55 it might, if desired, be carried entirely about it under the supporting member or otherwise.

Having described my invention, I claim—

1. The combination with a journal-box and a journal therein, of a dust-guard comprising 60 a member supported above the journal in a fixed position and serving as a guard for a portion of the opening between such journal and the box, and a flexible guard surrounding the remainder of the journal in contact therewith.

2. The combination with a journal box and a journal therein, of a dust-guard comprising

a member supported above the journal in a fixed position and serving as a guard for a portion of the opening between such journal and the box, and a flexible guard surrounding the remainder of the journal in contact therewith and secured to the member. 70

3. The combination with a journal-box and a journal therein, of a dust-guard comprising 75 a member supported above the journal in a fixed position and serving as a guard for a portion of the opening between said journal and the box; a flexible guard surrounding the remainder of the journal in contact therewith; and means for exerting tension circumferentially upon said flexible guard. 80

4. The combination with a journal-box and a journal therein, of a dust-guard comprising 85 a member supported above the journal in a fixed position and serving as a guard for a portion of the opening between said journal and the box; a flexible guard surrounding the remainder of the journal in contact therewith; and means attached to said member 90 for exerting tension circumferentially upon said flexible guard.

5. The combination with a journal-box and a journal therein, of a dust-guard comprising 95 a member in a fixed position provided with a wear-resisting shoe contacting with the journal and serving as a guard for a portion of the opening between said journal and the box; and a flexible guard surrounding the remainder of the journal. 100

6. The combination with a journal-box and a journal therein, of a dust-guard comprising a member in a fixed position above said journal and contacting with a portion of its circumference, and a flexible strip surrounding 105 the remainder of the circumference of the journal and having a spring connection to said member.

7. The combination with a journal-box and a journal therein, of a dust-guard comprising 110 a frame located in proximity to said journal; a member contacting with the journal and removably secured to said frame above said journal; and a flexible strip surrounding the journal and connected to said member. 115

8. The combination with a journal-box and a journal therein, of a dust-guard comprising a frame located in proximity to said journal; a member mounted in said frame above the journal; a movable piece secured to the member and engaging the frame to separably connect the two; and a flexible strip surrounding 120 the journal and connected to said member.

9. The combination with a journal-box and a journal therein, of a dust-guard comprising 125 a frame surrounding said journal and located in proximity to the inner face of the rear portion of said box, and a looped strip of yieldable material secured to the frame, the loop projecting beyond the surface thereof and 130 extending entirely around said frame and adapted to contact with said face.

10. In a dust-guard, the combination with a frame, of a member located within and se-

- cured to said frame and supporting the said frame, and a flexible strip connected to said member.
11. In a dust-guard, the combination with 5 a frame, of a supporting member and a flexible strip therein, said supporting member being secured to said frame and a spring connection between said member and strip.
12. In a dust-guard, the combination with 10 a frame, of a rigid member located within said frame and above the journal; a fastening device to separably secure the two together; and a flexible strip connected with said member.
13. In a dust-guard, the combination with 15 metal side plates, of interposed filling-pieces closing a plurality of the sides of said frame, and a flexible strip about the inside of said filling-pieces.
14. In a dust-guard, the combination with 20 a member adapted to rest upon a journal, of a flexible strip having its ends in contact with the ends of said member, and means secured to said member for drawing the strip toward it.
15. In a dust-guard, the combination with 25 a member provided with a wear-resisting shoe adapted to rest on a journal, said member being positioned above said journal, of a flexible strip in contact with the ends of the member.
16. In a dust-guard, the combination with 30 a member adapted to rest upon a journal, of a flexible strip provided with a backing having its ends connected with said member.
17. In a dust-guard, the combination with 35 a member adapted to rest upon a journal, of a flexible strip provided with a backing having its ends connected to springs carried by said member.
18. In a dust-guard, the combination with 40 a frame provided with an opening at one side, of a member within the frame and secured thereto in proximity with the opening above the journal, and a flexible strip connected to said member and adapted to contact with a 45 journal.
19. In a dust-guard, the combination with 45 a frame provided with an opening at one side, of a member located within the frame and separably attached thereto in proximity to 50 the opening above the journal, and a flexible strip connected to the member and adapted to contact with a journal.
20. In a dust-guard, the combination with 55 a frame provided with an opening at one side, of a member provided within the frame in proximity with the opening, and a flexible strip connected through springs to the member.
21. In a dust-guard, the combination with 60 a frame provided with an opening at one side, of a member located within the frame and secured thereto in proximity with the opening above the journal, and a flexible strip connected to the member and extending toward the opening and about the interior of the 65 frame.
22. In a dust-guard, the combination with 70 a frame provided with an opening at one side, of a member located within the frame in proximity to the opening, and a flexible strip provided with a backing having its ends connected with the side of the member toward the opening.
